UNITED STATES PATENT OFFICE.

MARVIN S. WEAVER, OF JOHNSON CITY, TENNESSEE.

MACHINE FOR SHARPENING CUTTING INSTRUMENTS.

1,076,801.

Specification of Letters Patent.

Patented Oct. 28, 1913.

Application filed April 22, 1912. Serial No. 692,280.

To all whom it may concern:

Be it known that I, MARVIN S. WEAVER, a citizen of the United States, residing at Johnson City, in the county of Washington and State of Tennessee, have invented a new and useful Improvement in Machines for Sharpening Cutting Instruments, of which the following is a specification, reference being had to the accompanying drawing.

My improvement relates particularly to apparatus for sharpening razors and other blade-form cutting instruments.

The chief object of the invention is to provide a mechanism adapted to serve as a substitute for a hand strop for the sharpening of razors and other blade-form cutting tools.

In the accompanying drawings; Figure 1 is front elevation of a machine embodying my improvement; Fig. 2 is a side elevation, looking toward the right in Fig. 1, the belts having been removed; Fig. 3 is a rear elevation, looking toward the right in Fig. 2; Fig. 4 is a horizontal section on the line, 4—4, of Fig. 1; Fig. 5 is a section on the line, 5—5, of Fig. 3; Fig. 6 is a section on the line 6—6, of Fig. 3.

Referring to said drawings, A, is a table or shelf to which my machine is applied, and B, is a cushion resting upon the table, A. The operative parts of the machine are mounted upon a base, 1. From the rear portion of the base rise two pedestals, 2, 2, each having a horizontal bearing, 3. In the form shown in the drawings, said pedestals are integral with said base. At the front of the base and opposite each pedestal is a standard, 4, secured to the base by set screws, 5, and each having in its upper end a horizontal bearing, 6, horizontally in line with the bearing, 3, in one of the opposite pedestals, 2. From each pedestal rises a column, 7, which, in the form shown, is integral with its pedestal. Each column has an upright groove, 8 forming a screw seat. A yoke, 9, loosely surrounds each column and is adjustable up and down by means of an upright supporting screw, 10, the lower end of which rests upon the column, 7. A set-screw, 11, extends horizontally through the yoke and into the groove, 8, to prevent rotation of the yoke and to bind the yoke against upward movement. In the portion of the yoke above the column, 7, is a horizontal bearing, 12, and horizontally opposite said bearing is another bearing, 13, in which is

a bearing block, 14, adapted to be driven upward by the upright screw, 15. The yoke, 9, is a movable section, and the portion thereof which surrounds the column forms a socket which is at one side of said section so that the bearings of said section are at one side of the axial line of said column.

Two parallel pulleys, 16, have shafts, 17, one end of each shaft resting in one of the bearings, 3, and the other end resting in the opposite bearing, 6. Two similar pulleys, 18, have shafts, 19, resting similarly in the bearings, 12 and 13, the forward ends of said shafts resting on the bearing blocks, 14. For convenience in description, the two pulleys (16 and 18) at the same side of the machine will be regarded as a pair.

Each pedestal and the column, yoke, and pulleys applied thereto constitute a support for a strop or belt, as hereinafter described.

Each of the shafts, 17, is extended rearward of its pedestal, 2, far enough to receive a worm gear wheel, 20. Said two worm gear wheels mesh with a worm, 21, located between said wheels and mounted on an upright shaft, 22, which extends downward through an opening, 23, in the base, 1, and an opening, 24, in the table, A. A motor, C, is applied to said shaft for driving the latter, and said motor is secured to the lower face of the table by means of brackets, 25. The two pulleys of each pair, the lower pulley and the upper pulley on the same support, are surrounded by an endless strop or belt, 26, each strop having a flat face opposite and adjacent a corresponding face on the other belt; and in the particular form shown by the drawings, said faces are parallel to each other, the four pulleys having the same diameter and the axes of the pulleys of each pair being in an upright plane. The two pairs of pulleys are separated sufficiently to leave a space a little more than the thickness of a blade—blade thickness—between the adjacent faces of the two strops or belts when the latter have been applied to the pulleys. An upright rest, 27, rises from the base, 1, between the two standards, 4, and in front of the two lower pulleys and is secured to the base, 1, by means of a set-screw, 28. (See Figs. 2 and 4.) Said rest may rise to any desired height suitable for supporting a blade, D, extending between the two strops or belts, 26.

For allowing the belts to be put into position on the pulleys, the standards, 4, are

removed by withdrawing the screws, 5, the standards being replaced when the belts have been applied. Any desired tension is given to the belts by forcing the yokes, 9, upward by means of the supporting screws, 10. The front end of the shaft, 19, may be further adjusted by means of the screw, 15.

The belts or strops are formed of a material and with an exterior working face 10 having a finish or dressing adapted to the sharpening of blade-form cutting tools like razors, carving knives, etc., by a stropping operation—the relative movement of the cutting tool and the strop one on the other, the 15 tool resting flatwise against the working face of one or the other of the strops. The working faces of the strops may be varied in dressing or finish for fine or relatively coarse work. The motor shaft and worm 20 are driven in the proper direction for turning the adjacent portions of the worm wheels upward, so that the adjacent portions of the two belts or strops will travel upward.

25 In operation, the blade of the razor or other cutting tool, D, to be stropped, is placed into the blade space between the adjacent faces of the strops, 26, above the rest, 27, with the back of the blade downward 30 and the edge upward, (see Figs. 1 and 2), the strops being in motion and the adjacent portions or faces moving upward as above described. The blade is pressed sidewise and flatwise against one of the strops and 35 then against the other, the alternation of application of the two sides of the blade being made approximately as is done while stropping on the ordinary hand strop. While the blade is free from the strops or while it 40 is in contact with one of them, the blade may be moved forward and rearward so as to make all portions of the edge in turn bear against the strops; and while the blade is lying flatwise against one of the strops, the 45 length of the blade may be kept at right angles or turned diagonally to the length of the strop.

For the purpose of analyzing this apparatus, it may be assumed that an upright 50 plane extends through the machine midway between and parallel to the adjacent faces of the two strops and the two pairs of pulleys. The knife or blade, D, which is to be sharpened lies in said plane when said blade is 55 midway between the adjacent portions of the belts and is upright—edge up and back down. During the sharpening operation, said knife oscillates through said plane, the movement having its axis along the back of 60 the blade. But the back of the blade may also be moved sidewise, if the space between the adjacent belt faces is relatively wide. Hence said plane may be called the "blade plane" and the space along said plane, be- 65 tween said belts, and forward and rearward

of said belts as far as the blade ordinarily extends during the sharpening operation, and above said belts used for the insertion and removal of said blade, may be termed the "blade space." It may be stated that 70 the belt supports are distinct and separated or isolated from each other above the lowest point to which the blade may extend and that the "blade space" extends between and forward and rearward of and above the adjacent faces of the strops. The blade space thus provided allows the movement of the blade forward and backward and upward and downward without bringing the edge of the blade into contact with anything else 80 than the strops. The lower portion of such blade space is terminated by the upper end of the motor shaft, 22, and the knife rest, 27, when the latter is used. Said rest is not an essential but merely a convenience. The 85 blade may be held by the hand of the operator so as to be supported by said rest or so as to be entirely clear thereof. And said rest, when used, may be of any desired height. Extending the blade space above 90 the strops is important in view of the fact that the strops tend to lift the blade and may do so when the grip of the hand on the blade is inadvertently released.

For different kinds of work, the tension 95 on the belts or strops may be varied by adjusting the yokes, 9, by means of the supporting screws, 10, as already described.

It is to be observed that the blade is kept in proper relation with the working face of 100 one strop and then the other; and it is to be observed that the velocity of linear travel of these endless strops over the side of the blade can be made much greater than can the converse movement of the blade over the 105 strop by hand stropping. In practice, it has been feasible to make the strops of my machine travel several hundred feet per minute.

A number of pairs of strops differing in 110 the finish or dressing of their working faces may be applied interchangeably to the pulleys for fine and coarse stropping.

Movement of the mechanism for adjusting the belts is parallel to the belts. Hence 115 the parallel relation of the adjacent portions of the paths of the belts is not disturbed by any adjustment of tension. The adjacent faces of the two belts remain parallel to each other and at the same distance from 120 each other.

By placing the adjacent faces of the belts parallel to each other, the relation of the blade to the adjacent faces of the belts remains the same when the blade is turned out 125 of the horizontal so that the length of the blade is placed diagonally (Fig. 2), instead of at right angles to the length of the adjacent strop faces.

Since the two adjacent belt faces are sepa- 130

rated from each other, either side of the blade may be pressed against the adjacent belt as long as may be desired for reducing that side of the blade. Furthermore, the 5 blade may be held at any height and yet the sidewise movement of the blade to make engagement with the belts will be the same.

It is also to be noted that, since the knife 10 is held by the hand, it can easily be put into position and quickly removed for inspection. No holding mechanism to which the knife must be fitted and secured is necessary.

By placing the working portions of the two 15 endless strops upright, gravity does not act unequally upon the blade to be sharpened. If said working faces were horizontal, the weight of the blade and the weight of the hand would be added to the muscular action of the hand and arm when the blade is 20 turned against the lower strop, and when the blade is turned to bear against the upper strop, the weight of the blade and hand would decrease the upward pressure exerted by the hand. By placing the working 25 faces of the belts upright and placing the rest, 27, across the blade plane, said rest may support the weight of the hand and the blade so that only muscular effort is involved in applying the blade to said 30 working faces. This allows a delicate manipulation. Furthermore, the manipulation is balanced, being the same at each side of the blade plane.

I claim as my invention:

35 1. In an apparatus of the nature described, the combination of two belts, two upright belt supports the upper portions of which are isolated and apart from each other and each comprising a stationary portion 40 having horizontal bearings for a pulley and a movable section having horizontal bearings for a pulley, the stationary portion comprising a column, and said movable section having an upright socket receiving the 45 upper end of said column, said socket being at one side of said section so that the bearings of said section are at one side of the axial line of said column, an adjusting screw extending downward through said section and bearing upon the upper end of said column, pulleys having journals in said bearings, one of said belts being mounted on one pair and the other on the other pair of said pulleys and said pairs of pulleys being separated a proper distance to separate the 50 adjacent faces of the belts by a blade space a little wider than blade thickness, and means for driving said pulleys for moving said adjacent faces upward, substantially as described.

55 2. In an apparatus of the nature described, the combination of two belts, two upright belt supports the upper portions of which are isolated and apart from each other and each comprising a stationary por-

tion having horizontal bearings for a pulley and a movable section having horizontal bearings for a pulley, the stationary portion comprising a column, and said movable section having an upright socket receiving 70 the upper end of said column, said socket being at one side of said section so that the bearings of said section are at one side of the axial line of said column, an adjusting screw extending downward through said section and bearing upon the upper end of said column, pulleys having journals in said bearings, one of said belts being mounted on one pair and the other on the other pair of said pulleys and said pairs of pulleys being separated a proper distance to separate the adjacent faces of the belts by a blade space a little wider than blade thickness, and means for driving said pulleys for moving 75 said adjacent faces upward, a bearing block 80 in one of the bearings of said upper section, and means for raising said block, substantially as described.

3. In an apparatus of the nature described, the combination of two belts, two 90 upright belt supports the upper portions of which are isolated and apart from each other and each comprising a stationary portion having horizontal bearings for a pulley and a movable section having horizontal 95 bearings for a pulley, the stationary portion comprising a column, and said movable section having an upright socket receiving the upper end of said column, said socket being at one side of said section so that the bearings of said section are at one side of the axial line of said column, an adjusting screw 100 extending downward through said section and bearing upon the upper end of said column, pulleys having journals in said bearings, one of said belts being mounted on one pair and the other on the other pair of said pulleys and said pairs of pulleys being separated a proper distance to separate the adjacent faces of the belts by a blade 105 space a little wider than blade thickness, and means for driving said pulleys for moving said adjacent faces upward, a bearing block 110 in one of the bearings of the upper sections, and extending upward through said section and against said block, substantially 115 as described.

4. In an apparatus of the nature described, the combination of two belts, two 120 upright belt supports the upper portions of which are isolated and apart from each other and each comprising a stationary portion having horizontal bearings for a pulley and a movable section having horizontal bearings for a pulley, the stationary portion 125 comprising a cylindrical column having an upright screw seat and said movable section having an upright socket receiving the upper end of said column, said socket being at one side of said section so that the bearings 130

of said section are at one side of the axial line of said column, a screw extending horizontally through the wall of said socket against said screw seat, an adjusting screw 5 extending downward through said section and bearing upon the upper end of said column, pulleys having journals in said bearings, one of said belts being mounted on one pair and the other on the other pair 10 of said pulleys and said pairs of pulleys being separated a proper distance to separate the adjacent faces of the belts by a blade

space a little wider than blade thickness, and means for driving said pulleys for moving said adjacent faces upward, substantially as described. 15

In testimony whereof I have signed my name, in presence of two witnesses, this fifteenth day of April, in the year one thousand nine hundred and twelve.
